UNITED STATES PATENT OFFICE.

FRIEDRICH MEX, OF MOSCOW, RUSSIA.

PETROLEUM-MOTOR.

SPECIFICATION forming part of Letters Patent No. 562,230, dated June 16, 1896.

Application filed June 21, 1895. Serial No. 553,511. (No model.) Patented in England May 20, 1895, No. 9,964; in France May 20, 1895, No. 247,550; in Switzerland May 20, 1895, No. 10,444; in Belgium May 21, 1895, No. 115,717, and in Hungary October 26, 1895, No. 4,009.

To all whom it may concern:

Be it known that I, FRIEDRICH MEX, a subject of the Czar of the Russian Empire, and a resident of Moscow, in the Russian Empire, have invented certain new and useful Improvements in Petroleum-Motors, (for which I have obtained patents in Belgium, No. 115,717, dated May 21, 1895; in Great Britain, No. 9,964, dated May 20, 1895; in France, No. 247,550, dated May 20, 1895; in Switzerland, No. 10,444, dated May 20, 1895, and in Hungary, No. 4,009, dated October 26, 1895,) of which the following is a specification.

This invention has reference to an improved petroleum-motor of that class which are known as "single-stroke" motors, in which every stroke of the piston is a power stroke, while the well-known petroleum-motors are usually arranged on the so-called "four-stroke" principle. The single-stroke effect is obtained by arranging alongside of the working cylinder a supply-cylinder, the piston of which alternately sucks in petroleum-vapors and forces the same into the working cylinder, which suction and supply are regulated by means of suction and intermediate supply valves, the latter being actuated by connecting-rods from eccentrics on the driving-shaft, so as to produce the proper communication between the working and supply cylinders. The suction-valves of the motor are connected with suitable petroleum-vaporizers in which dry vapors are produced, so that no gummy or other sediments are produced in the working cylinder.

The invention consists of a petroleum-motor comprising a working cylinder, a supply-cylinder for the working cylinder, discharge-valves for the working cylinder, suction and intermediate supply valves for the supply-cylinder, connecting-channels between the working cylinder and the intermediate supply-valves of the supply-cylinder, pistons in said cylinders, the piston in the supply-cylinder being arranged and adapted to move somewhat in advance of that in the working cylinder, eccentrics on the driving crank-shaft, and connecting-rods between the eccentrics on the driving-shaft and the discharge

and intermediate supply valves, respectively, so as to produce the regular supply of vapors for the compression and combustion of the same, and also to produce the discharge of the heated gases which are conducted to the vaporizers that are arranged in connection with the suction and discharge valves, as will be fully described hereinafter, and finally pointed out in the claims.

In the accompanying drawings, Figure 1 represents a side elevation of my improved petroleum-motor. Fig. 2 is a plan view of the same, parts being shown in horizontal section through the working and supply cylinders. Fig. 3 is an end elevation showing one of the vaporizers and its connections with the cylinders in dotted lines. Figs. 4 and 5 are respectively a vertical longitudinal section and an end elevation, with the cover removed, of the vaporizer. Fig. 6 is an end elevation of the inner cone of the vaporizing-chamber, with the outer casing, to which it is attached, in section; and Fig. 7 is a longitudinal section of the inner cone.

Similar letters of reference indicate corresponding parts.

My improved motor consists of a working cylinder *a* and a vapor-supply cylinder *b*, in which are arranged pistons *c* and *d*, respectively, the piston-rods of which are so connected with the driving crank-shaft *D* that the piston *d* of the supply-cylinder is moved slightly ahead of the piston *c* of the working cylinder, as shown in Fig. 2. The working cylinder *a* is provided with two discharge-valves *h' h²*, which are actuated by a connecting-rod *h*, that is operated from the eccentric *h³* on the driving-shaft. The supply-cylinder *b* is provided with four valves, namely, two intermediate supply-valves *c' c²* and two suction-valves *d' d²*. The intermediate supply-valves *c' c²* are actuated by a connecting-rod *c³*, which is operated by an eccentric *c⁴* on the driving-shaft *D*. The suction-valves *d' d²* are connected with the petroleum-vaporizers, to be hereinafter described, so that the piston *d* sucks in the vapors during the forward-and-backward stroke of the same, and the intermediate supply-valves *c' c²* are

connected by pipes or channels r , on which are arranged the supports f of the igniter, with the working-cylinder a . Simultaneous operation of the outlet-valves h^1 h^2 is produced by the connecting-rod h by means of two pivoted actuating arms or levers h^3 h^4 , which engage the lower ends of the spindles of the valves and which are in turn engaged by the lateral projections h^5 h^6 of the connecting-rod h , so that when one of the valves h^1 h^2 is open the other is closed, and vice versa. The actuation of the intermediate supply-valves c^1 c^2 is produced by angular projections on the connecting-rod c^3 in similar manner.

15 My improved petroleum-motor is operated as follows: The piston in the supply-cylinder serves for sucking in the vapors into one end of the cylinder and for supplying the vapors, at the other end, simultaneously to the working cylinder. When the piston d moves in forward direction, the suction action of the same closes the intermediate supply-valve c^1 and opens the suction-valve d' . At the same time, the working cylinder a is charged with 25 vapors by the opening of the intermediate supply-valve c^2 , while the suction-valve d^2 is closed. The intermediate supply-valve c^2 is not opened by the connecting-rod c^3 until the products of combustion are forced by the piston c of the working cylinder a , through the outlet-valve h^2 , and the latter is closed again, so that the piston c is in the position shown in Fig. 2. In this position of the piston c , the supply of vapors from the supply-cylinder b takes place, the piston d of the supply-cylinder forcing the compressed vapors from the supply-cylinder into the working cylinder. The intermediate supply-valve c^2 is then closed, so that by the continued forward motion of the piston c the already compressed petroleum-vapors are still more compressed in the working cylinder. When the vapors are compressed to the highest point of compression, the outlet-valve h^2 and the intermediate supply-valve c^2 are closed and the ignition takes place.

40 The ignition can be accomplished in any approved manner, preferably by electrical means. The explosion of the vapors forces the working piston c in backward direction, so that the same successive operations can take place at the opposite side of the piston, namely, the discharge of the products of combustion filling the working cylinder with a new charge of vapors from the supply-cylinder, and the compression of these vapors at the opposite end of the working cylinder causing the ignition of the compressed vapors, so that the return stroke of the piston takes 45 place, and so on.

Both cylinders as well as the valves are cooled in any approved manner by means of water which is supplied into a jacket J of the working cylinder, then conducted into a jacket J' of the supply-cylinder, from which it is conducted off in any suitable manner. The piston and piston-rods may likewise be cooled

in any well-known manner, and a suitable safety-valve has to be provided on the supply-cylinder, so that in case of a premature ignition of the gas the bursting of the cylinder is prevented.

The construction of the petroleum-vaporizer is shown in Figs. 4 to 7. The vaporizers are constructed with a view so as to produce perfectly dry vapors, which, after combustion, do not leave any sediment in the working cylinder. For this purpose they are arranged on the motor and connected with the discharge-valves h^1 h^2 and the suction-valves d^1 d^2 . The vaporizer consists of an exterior casing m , which is provided at its larger end with a cover m' and at its smaller end with a screw-coupling x , and in the cover with a like coupling y .

In the exterior casing is arranged a vaporizing-chamber which is formed by two concentric cones n o , the inner cone o being provided with exterior circular flanges o' , fitted to the inner surface of the outer concentric cone n . The space between the flanges is filled with iron filings. The petroleum is supplied by means of a suitable pipe i and passes successively through the channels formed between the flanges o' in the direction of the arrow shown in Fig. 1. The vapors are discharged in perfectly-dry condition through the pipe g , which is connected with one of the suction-valves of the supply-cylinder. The products of combustion are conducted from the discharge-valves through the coupling x of the vaporizer and pass around between the same and the exterior cone n , so as to vaporize the petroleum in passing through said cone. The products of combustion pass off through the coupling y . Two of these vaporizers are arranged one in connection with each suction-valve of the supply-cylinder.

It is obvious that before starting the motor the vaporizer should be heated up by means of a lamp or other suitable heating device until the hot products of combustion are supplied from the discharge-valves to the ingoing ends of the vaporizers, so that they can heat up the petroleum and produce the vaporization of the same.

Having thus described my invention, I claim as new and desire to secure by Letters Patent—

1. In a petroleum-motor, the combination of a working cylinder provided with discharge-valves, a supply-cylinder arranged alongside of the working cylinder and provided with suction-valves and with intermediate supply-valves, pistons in said cylinders, the piston in the supply-cylinder being arranged and adapted to move somewhat in advance of that in the working cylinder, a vaporizer, pipe connections between the vaporizer and the suction and discharge valves, and means for actuating the suction, intermediate supply and discharge valves in such a manner that after the charge of vapors in the working cylinder is compressed the ignition and

combustion of the gas can take place, substantially as set forth.

2. In a petroleum-motor, the combination of a working cylinder and supply-cylinder, discharge-valves in the working cylinder, suction-valves and intermediate supply-valves for the supply-cylinder, pistons in said cylinders, the piston in the supply-cylinder being arranged and adapted to move somewhat in advance of that in the working cylinder, a vaporizer, pipe connections between the vaporizer and the suction and discharge valves, and the main shaft provided with eccentrics, and connecting-rods actuated by the latter and themselves actuating the discharge and intermediate supply valves, said connecting-rods being provided with projections, by means of which the valves are opened and closed alternately, substantially as set forth.

3. In a petroleum-motor, the combination with the working cylinder provided with discharge-valves and a discharge-cylinder provided with suction-valves and intermediate supply-valves, of a petroleum-vaporizer composed of an exterior casing and interior cones separated by concentric flanges forming channels which are filled with iron filings, said casing forming a space around the exterior cone through which the products of combus-

tion pass, so as to produce the heating and vaporizing of the petroleum, and pipe connections between the vaporizer and the suction and discharge valves, substantially as set forth.

4. A petroleum-vaporizer for petroleum-motors, composed of an exterior conical casing, an interior vaporizing-chamber composed of concentric cones, one of which is provided with concentric flanges forming a continuous serpentine channel and against which flanges the other cone is fitted, a pipe extending from the apex of the outer cone through the casing for supplying the petroleum to said channel, means for supplying the products of combustion to the space between the casing and the exterior vaporizing-cone, and a cover fitting onto the enlarged or flaring end of the casing and provided with an outlet-pipe for conducting off the products of combustion after the same have heated and vaporized the petroleum, substantially as set forth.

In testimony that I claim the foregoing as my invention I have signed my name in presence of two subscribing witnesses.

FRIEDRICH MEX.
